UNITED STATES PATENT OFFICE.

FRIVIRIE ROY, OF ST. BERNARD PARISH, LOUISIANA.

IMPROVEMENT IN FURNACES FOR EVAPORATING SUGAR-JUICES.

Specification forming part of Letters Patent No. 22,307, dated December 14, 1858.

To all whom it may concern:

Be it known that I, F. Roy, of the parish of St. Bernard, State of Louisiana, have made a new and useful Improvement in the Mode of Setting Kettles for Boiling Cane-Juice; and I hereby declare the following is a full and exact description thereof, reference being had to the accompanying drawings and the letters of reference marked thereon, making a part of this specification.

Figure 1 shows a ground plan representing that portion as seen below the lines *z* in Figs. 2 and 3, having the kettles supposed to be in their places, as shown by the numbers 1 2 3 4, the bagasse-drying compartments A B C represented at an elevation of the line cutting the letter K in the sectional elevation of the drier C, Fig. 2. So far as the ground plan, the other arrangement of the sugar-house will require to be consulted to allow the construction, the position as seen in this figure not being necessarily required to follow for the erection to secure efficiency. The driers A B C are built, the same as chimneys, at a height of twenty-five or thirty and about ten feet square, depending on the quantity of bagasse to be dried in a given time, this size given suitable for a medium quantity of cane to be ground. In the setting of the kettles I have a furnace under each kettle with grates and fire-doors made and arranged similar to the usual manner of doing this portion of the work, the kettles mounted over their furnaces, and have their support on the surrounding brick-work built under their upper ledges, with the tiling and other necessary arrangements the same as the common mode of setting kettles. In addition to this described solid pinning of brick-work, by which the kettles are usually mounted, I have a skeleton pinning reaching from the inside edges of the furnaces to the kettles, (seen in all numbers 1 2 3 4,) the brick-work making the pinning designated by the letter *i*, as seen at No. 2, and the open spaces between the brick-work designated by the letter *o*, the flame passing through the spaces *o* and falls into the chambers *h*, surrounding the kettles, and the flues, also marked *h*, which makes a connection of the different chambers around the kettles on the side of the brick-work, making the

wall for all the kettles. I construct a flue (marked *g*) for the purpose of carrying off the heated gas from the kettle-chambers and conveying the same to the drying-chambers, and admitted therein through the openings K K K, leading from the chambers *h* to the flue *g*. I have flues X, with a damper for each, to be closed or opened at pleasure, so the action of the heat from the several furnaces can be brought to bear on any particular kettle by the closing or the opening of the dampers, and thus secure a uniform evaporation. Instead of the flue *g*, should it be desired, a steam-boiler can be placed in the same position, and have the heat to act on the boiler before being conveyed to the drying-chambers. On the reverse sides of the kettles from X, and on the same level, I have a flue for each kettle, (marked *u*,) for the purpose of cleansing the chambers *h* when deposits of ashes are made, these flues having either a sliding or swinging door that can be opened when necessary to cleanse; or, should a suspension of the evaporation of the juice be required, the opening of the door *u* for the time, admitting cold air, will produce this effect.

Fig. 2 is a sectional side elevation taken from the line *z* of Fig. 1. This view reverses position from that of Fig. 1, in representing the drying-chambers situated at right angles with the kettles which are marked 1 2 3 4, showing furnaces *f*, grates *s*, ash-pits *a*, and upper fire-chambers, *h*, skeleton pinning *i*, all shown above *h*, (no reference given,) this portion being, as already stated, the same as usually constructed in the setting of kettles; the drying-chamber *c* sectional also, taken so from the line *z* through *c*, Fig. 1; *k*, the flue connecting the chambers with the flue *g*, having dampers *v*, for the purpose of admitting or suspending the heated gas from the different chambers when required. In the employment of three drying-chambers the bagasse can be discharged into one, and the drying can go on in another during the time the third is being emptied of the bagasse that has been already dried for use as fuel. The bagasse is admitted through the openings *P* after being conveyed from the sugar-mill by the carrier, and lodging on the grating *r*, and after being dried taken from the chambers through doors *b*.

Fig. 3 is a sectional transverse view showing ash-pit *a*, grates *s*, furnace-door *d*, furnace *f*, skeleton pinning *i*, upper fire-chamber, *h*, main flue *g*, connecting flue with fire-chamber and *g* marked X, dampers for same, *y*, flue above fire-doors *u*, the kettles represented by Fig. 2.

Fig. 4 is a side elevation of the furnace only, main flue leading to the driers *g*, ash-pits *a*, fire-doors *d*, flue-doors *u*.

I do not claim, broadly and of itself, the open setting of kettles; but

What I do claim is—

The setting of sugar-kettles with the system of radial braces *i i*, so situated as to divide the space around the kettles into two apartments communicating by the openings *o*, when these upper chambers communicate with each other, and by flues X with a common flue, *g*, the whole operating substantially as and for the purpose set forth.

FIRVIRIE ROY.
